TYPEWRITER CHARACTER SPACING
MEANS

Alden C. Waite, Santa Monica, Calif.

Application August 9, 1939, Serial No. 289,139

8 Claims. (Cl. 197—34)

My invention relates to a typewriter character spacing means, whose principal object is to provide means for variable spacing for typewriters so that the widths provided by the typewriter for different characters will depend upon the normal width of such characters and not be uniform irrespective of their width, as is the case with typewriters in general use.

Another object is to provide simple, effective means for selective typewriter spacing, for the purpose stated.

The invention also comprises novel details of construction and novel combinations and arrangements of parts, which will more fully appear in the course of the following description.

In the drawings, like reference characters designate similar parts in the several views.

Figure 1 is a broken elevation, partly in section, of an embodiment of the present invention.

Figure 2 is an enlarged, broken elevation taken on the line 2—2 of Figure 1.

Figure 3 is a section taken on the line 3—3 of Figure 2, looking in the direction of the arrows.

Figure 4 is an enlarged, broken plan taken on the line 4—4 of Figure 1.

Figure 5 is a broken elevation looking in the direction of the arrows 5—5 of Figure 4.

Figure 6 is a broken elevation of a selector, comprised in the invention, taken on the line 6—6 of Figure 4.

Figure 7 is a broken view of the upper portion of an escapement frame and associated parts, looking in the opposite direction from Figure 2.

The present drawings do not show a complete typewriter but only applicant's embodiment together with associated parts of a typewriter. A carriage (not shown) is mounted on a supporting arm 7 which is pivoted at 8 on a base 9. A spring 10 resiliently supports the carriage on the base 9, by means of the pivoted arm 7. A toothed bar 12 is mounted on the base member 9 and travels with the carriage. The usual spring for actuating the carriage is not shown. A fixed portion 13 of a typewriter supports brackets 14 in which is pivoted an escapement frame 15 by means of a pin 16 that extends from one bracket 14 to the other.

A fixed pallet 17 is bolted to the escapement frame 15, while a sliding pallet 18 is formed on a sliding bar 19. The sliding bar is slotted as shown at 20, whereby the bar 19 may slide on pins 21 and is held thereon by heads 22. A coil spring 23 tends to move the bar 19 to a position in which the movable pallet 18 is aligned laterally with the fixed pallet 17. The spring (not shown)

which actuates the carriage is a stronger spring than the spring 23.

Pivotedly mounted on the pin 16 within the escapement frame 15 is a series of pivoted arms 24, 25 and 26. The arms 24, 25 and 26 have hooked fingers 27, 28 and 29 at their lower ends. Pins 30, 31 and 32 are slidably in bores 33 on the upper portion of the escapement frame 15. The pins 30, 31 and 32 are respectively actuated by the pivoted arms 24, 25 and 26 against the action of springs 34. The pins have pivotal connections 35 with the arms. The distances between teeth on the bar 12 are identical with the distances between the pins 30, 31 and 32. A rod 36 connects the escapement frame 15 with appropriate operating mechanism of the typewriter, in order to rock the escapement frame 15 with the typing of each character and with each spacing between characters.

A selector 37 has a hooked end 38. The selector 37 is moved laterally by means hereinafter to be described and in its laterally adjusted positions, it engages one of the hooked ends 27, 28 or 29 of the pivoted arms. In Figures 1 and 2 it is shown as engaging the hooked end 27 of the pivoted arm 24. The selector 37 has a pivotal connection 39 with a neck 40. A spring 41 tends to maintain the selector 37 and the neck 40 in alignment with each other, as shown in Figure 6, but the pivoted connection 39 permits the selector 37 to be depressed downward against the action of the spring 41, which spring 41 tends to return the selector to its position of alignment with the neck 40.

A cross-head 42 is mounted on the neck 40. Headed pins 43 are disposed in a slot 44 in the cross-head, and such pins limit lateral movement of the cross-head 42. A nose 45 is mounted on the cross-head 42 and projects outwardly therefrom. A bracket 46 on the frame of the typewriter supports the sliding cross-head 42 and the pins 43 and is in turn supported on a sleeve 47 on the typewriter frame.

A plurality of reciprocating bars 48, 49 and 50 are movable in the sleeve 47. The bars 48, 49 and 50 have at their upper ends respectively notches 51, 52 and 53. The bottoms of these notches are out of alignment with each other, as best shown in Figures 4 and 5. The bars 48, 49 and 50 respectively have feet 54, 55 and 56 at their lower extremities.

Rocker arms 57, 58 and 59 are pivotally mounted on a bar 60 and respectively lift the bars 48, 49 and 50. The rocker arm 57 actuates the bar 48 through the intermediary of a sliding rod 61 in a

sleeve 62. The rocker arms 57, 58 and 59 are respectively actuated by bars 63, 64 and 65 by means of lugs 66, 67 and 68 on the bars respectively. The rocker arms 57, 58 and 59 have shoulders 69, 70 and 71.

It is to be understood that for every type bar of the typewriter there is a corresponding bar similar to 63, 64 or 65. Thus all of the narrower characters will have bars corresponding to bar 65 which have lugs at the same elevation as lug 68. All of the medium sized characters will have bars similar to bar 64 and will have lugs at the same elevation as lug 67. All of the wider characters will have bars similar to bar 63 which will have lugs of the same elevation as the lug 66. All the lugs of the same elevation as the lug 68 bear upon the shoulder 71, all the lugs of the same elevation as the lug 67 bear upon the shoulder 70, and all the lugs of the same elevation as the lug 66 bear upon the shoulder 69.

Therefore, in the operation of the present invention, when one of the keys is depressed to print a wide character, the arm 57 is rocked, as shown in Figure 1, thus raising the sliding bar 48. The slotted end of the bar 48 causes the pin 45 to bottom in the notch 51 of such sliding bar. This causes the selector 37 to be moved, by means of the cross-head 42, to a position in which said selector engages the hooked end 27 of the pivoted arm 24. The pivotal connection 39 permits the selector hook 38 to pass under the hooked end 27 during movement of the hooked end of the pivoted arm past the hooked end 38 of the selector.

35 The movable pallet 18 is in engagement with the toothed bar 12 when the carriage is in a stationary position (such as shown in Figure 2). When a key or the space bar is depressed, the rod 36 rocks the escapement frame 15, thus releasing the pallet 18 from the toothed bar 12 and causing the fixed pallet 17 to maintain the toothed bar 12 and hence the carriage in its same position. When the escapement frame 15 is thus rocked, the hooked ends 27 to 29 are all put in a position 40 to be engaged by the hooked end of the selector 37, but the rocker arms 57 to 59 have determined the position of the selector 37, depending upon the width of the character, in the manner heretofore described.

50 Upon release of the key or space bar, the escapement frame 15 is allowed to rock back to its vertical original position, but one of the pivoted arms 24 to 26 is held in the rocked position by reason of its hooked end being in engagement 55 with the hooked end of the selector 37. The pivoted arm 24 has been held in the rocked position by the selector, in Figure 1. This causes the pin 30, actuated by the arm 24, to be moved outwardly from its bore 33 and into the path of the foot 80 of the movable pallet 18. Thus when the escapement frame 15 is rocked back to its vertical position, the fixed pallet 17 is moved from engagement with the toothed bar 12 and the movable pallet 18 is moved into engagement 60 with the same tooth of the bar 12, since the spring 23 has returned the movable pallet 18 to a position of lateral alignment with the fixed pallet 17. Thereupon the spring (not shown) on the carriage moves the carriage, the toothed bar 12 and the movable pallet 18 until the foot 80 of the movable pallet contacts the pin 30. Since the pin 30 is farthest from the fixed pallet, the movement just described will be used for the widest 65 letters. It will be noted that the movement of

the carriage takes place after the type bar has done its printing.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications which may fall within the scope of the appended claims.

Having thus described my invention, what I claim and desire to secure by Letters Patent is:

1. In spacing means for a typewriter having a toothed bar, an escapement comprising a rocking frame, relatively fixed and movable pallets on the frame, the pallets being arranged for one or the other to engage the toothed bar in the rocked positions of the frame, a series of pivoted arms swingable with, and in respect to, the rocking frame having means to limit movement of the movable pallet to different distances of movement, and a single member operatively shiftable by keys on the typewriter to select and check movement of one or another of said arms, to limit the distance of the movement of the movable pallet to different distances, depending upon the varying widths of characters represented by the keys.

2. In spacing means for a typewriter having a toothed bar, an escapement comprising a rocking frame, relatively fixed and movable pallets on the frame, the pallets being arranged for one or the other to engage the toothed bar in the rocked positions of the frame, a plurality of means mounted to rock with, and in respect to, the frame and having members individually movable into the path of the movable pallet, spring means on the frame tending to move said means for shifting said members out of said path, and mechanism operable by keys on the typewriter to check the rocking movement of one or another of said means for interposing the movable member thereof into the path of the movable pallet, against the action of said spring means when the frame is rocked, the said members thereby limiting the distance of the movement of the movable pallet to different distances, depending upon the varying widths of characters represented by the keys.

3. In spacing means for a typewriter carriage, an escapement comprising a rocking frame, arms pivoted to rock with, and in respect to, the frame, in connection with each arm and arranged to limit movement of the carriage when the respective arm is held against rocking movement with the frame, means connected to rock the escapement frame for each key that is struck, the arms having individual hook means, selector mechanism arranged to be operated by keys of the typewriter and connected to select predetermined arms, and means carried by said selector mechanism to engage the hook of a selected arm to hold such arm against movement when the frame is rocked, said first named means limiting movement of the carriage to different distances, depending upon the varying widths of characters represented by the keys.

4. In spacing means for a typewriter carriage, an escapement comprising a rocking frame, arms pivoted to rock with, and in respect to the frame, means on the arms in connection with each arm to limit movement of the carriage when the respective arm is held against movement with the frame, means connected to rock the escapement frame for each key that is struck, the arms being

arranged side by side, selector means movable laterally along, and in engagement with, said arms and by such movement being arranged to select an arm and to maintain a selected one of 5 the arms against movement when the frame is rocked, said means on the arms being positioned to limit movement of the carriage to different distances, depending upon the varying widths of characters represented by the keys, and means 10 operable by the keys of the typewriter and in turn actuating the selector means.

5. In spacing means for a typewriter carriage, escapement mechanism having means to limit movement of the carriage varying distances, a 15 selector movable to different positions, a plurality of arms arranged to respectively engage the selector in its different positions and individually, operatively connected to said means to limit movement of the carriage varying distances, and 20 mechanism connected to be operated by the keys of the typewriter and to move the selector to its different positions, depending upon the varying widths of the characters on the individual keys.

6. In spacing means for a typewriter carriage, 25 means to limit movement of the carriage varying distances, a selector movable to different positions, means respectively actuated by the selector in its different positions and in turn operating said means to limit movement of the carriage 30 varying distances, and sliding bars connected to move the selector to different positions, the bars

being connected with keys of the typewriter, depending upon the varying widths of characters represented by the keys.

7. In spacing means for a typewriter carriage, means to limit movement of the carriage varying 5 distances a selector movable to different positions, mechanism connected to be operated by the selector and in turn arranged to selectively actuate said means, to limit movement of the carriage varying distances, and sliding bars connected 10 to be operated by keys of the typewriter, depending upon the varying widths of characters represented by the keys, the bars having differently positioned notches therein presenting selector actuating surfaces to engage and 15 move the selector to different positions.

8. In spacing means for a typewriter carriage, means to limit movement of the carriage varying distances, a selector movable to different positions, mechanism connected to be operated by the 20 selector and in turn arranged to selectively actuate said means, to limit movement of the carriage varying distances, a cross-head on the selector, and sliding bars connected to move the cross-head to different positions and thereby 25 move the selector to different positions, the bars being connected with keys of the typewriter, depending upon the varying widths of characters represented by the keys.

ALDEN C. WAITE. 30
